G. T. MOORE

COMBINED STREET INDICATOR AND ADVERTISING DEVICE

Filed June 3, 1922

UNITED STATES PATENT OFFICE.

GEORGE T. MOORE, OF ST. LOUIS, MISSOURI.

COMBINED STREET INDICATOR AND ADVERTISING DEVICE.

Application filed June 3, 1922. Serial No. 565,553.

To all whom it may concern:

Be it known that I, GEORGE T. MOORE, a citizen of the United States of America, and a resident of the city of St. Louis and State 5 of Missouri, have invented certain new and useful Improvements in a Combined Street Indicator and Advertising Device, of which the following is a specification.

The primary object of this invention is 10 to provide an improved street indicator for street cars which is operated by the conductor of the car so as to disclose to the passengers of the car the name of the next street intersection or car stop.

Another object of this invention is to 15 provide a street indicator with a series of flaps or cards each bearing a street name or number as well as advertising matter, and in which only one flap or card at a time will be disclosed to the passengers of the car.

A further object of the invention is to 20 provide a street car indicator which is comprised of a revoluble member bearing a series of flexible show cards, each being adapted to be intermittently displayed and in which the revoluble element is turned in one direction during the entire round trip of the street car.

A still further object of the invention is 25 to provide a street car indicator bearing a plurality of display cards with improved means whereby the cards can readily be removed and new cards introduced.

Other and further objects will appear in 30 the specification and be specifically pointed out in the appended claims, reference being had to the accompanying drawings, exemplifying the invention, and in which:—

Figure 1 is a transverse vertical section 35 taken through the upper portion of a street car looking towards the forward end thereof and to which this improved street indicating device is applied.

Figure 2 is an enlarged fragmentary longitudinal section taken approximately on the line II—II of Fig. 1.

Figure 3 is an enlarged vertical section 50 taken approximately on the line III—III of Fig. 2, and showing the lid of the housing in open position.

Figure 4 is a vertical section taken approximately on the line IV—IV of Fig. 3, and included in said figure is an electrical

circuit for bringing on the operation of this improved device. 55

Figure 5 is a vertical section taken approximately on the line V—V of Fig. 3.

Figure 6 is an enlarged fragmentary vertical section taken on the line VI—VI of Fig. 1. 60

Referring by numerals to the accompanying drawings 1 designates the forward end of a street car having a cross member 2 arranged beneath the roof 3, and secured to said cross member is a pair of brackets 4, and engaged in each of said brackets is a depending portion 5 of a respective supporting arm 6, said arm being horizontally extended and each being secured to a respective side wall 7 to a housing 8. 70

The extending end of each of the arms 6 is provided with a bearing 9, and turnably supported within said bearings is a horizontally arranged shaft 10, and rigidly secured to said shaft adjacent each respective end wall 7 within the housing 8 are respective sign carrying members 11 and 12, the member 11 being provided with a plurality of notches 13 on its outer periphery, whereas the member 12 is provided with a plurality of openings 14 which are equal in number to the notches 13 of the member 11. 75

The shaft 10 and the pair of members 11 and 12 are for the support of a plurality of sign cards 15, said sign cards being comprised of a body of material such as paper or canvas, the upper end 16 of each body being secured to a rod 17, each rod of each sign card being secured at one end to a respective opening 14 whereas the opposite end of each rod is engaged within a respective notch 13, and when each respective pair of alining notches and openings 13 and 14 are engaged with respective rods of sign cards, the supporting members 11 and 12 80 therefore will assume the form of a drum. 85

Rigidly secured to the shaft 10 on the outside of the member 12 is a ratchet wheel 18, said wheel being provided with teeth 19 on its periphery which are equal in number to 100 the number of sign cards borne by the members 11 and 12, and swingably mounted on said shaft 10 adjacent said ratchet wheel 18 is an upwardly extending arm 20, said arm bearing a spring pressed pawl 21 adjacent 105 its upper end, said pawl adapted to engage

the teeth 19 of said ratchet wheel, and connected at one end to said arm and at its opposite end at 22 to the adjacent end wall 7 is a coil spring 23, and projecting from said 5 end wall 7 is a stop 24 for co-operation with said arm.

Borne by the end wall 7 which is adjacent the arm 20 is a magnet 25, and leading from said magnet is a wire 26 of an electric circuit 27, said wire 26 leading to a circuit closing button 28 which is located at the rear end of the street car adjacent the conductor thereof. A wire 29 is extended from the button 28 to a source of electrical energy 30 10 such as a battery or the like, and leading from said electrical source is a wire 31 which is extended to and contacts with the arm 20. The housing 8 in which is contained the drum bearing the plurality of sign cards 15 15 is provided with an under formed opening 32 as shown more clearly in Figs. 4, 5 and 6, and formed in the top of the housing is an opening 33 which is adapted to be closed by a swingable cover plate 34, said opening 33 20 providing access to adjacent rods 17 of respective sign cards 15 so that the sign cards can be removed in groups for making a 25 change of the cards, if desired.

Each of the sign cards 15 is provided with 30 a horizontally extended rod 35, each rod 35 being oppositely disposed to a respective rod 17 of each sign card, and in the order of arrangement of the sign cards on the drum which is comprised of the members 11 and 35 12 and the sign cards mounted thereon, said sign cards will assume overlapping positions to one another, with the exception of those adjacent the opening 32 of the housing 8.

In the operation of a device of this improved character, the number of sign cards used will be approximately twice the number of blocks or street intersections at which the street car is scheduled to stop on either of its in or out bound trips, for instance, 40 assuming that the length of a run is 33 blocks, the return trip will also include 33 blocks, therefore the number of sign cards to be used will be approximately 66, as it is deemed that the drum bearing the sign cards 45 will be continually rotated in the same direction.

Let it be assumed that a car has just started on its downtown trip, therefore the first sign displayed will be that disclosing 33rd 50 Street, and as the car approaches the next block will be 32nd Street, the conductor upon pressing the button 28 will close the circuit 55 27 thereby causing the magnet 25 to act and draw upon the armature 36 which is borne by the arm 20, said arm causing the pawl 21 to turn the ratchet wheel 18 the distance of the length of one of its teeth in which the shaft 10 will be turned and the rod 35 of the 32nd sign card will be moved from engagement with the retaining spring 37, in 60 65

which the sign card 15 as representing 32nd Street will be allowed to fall and unfold downwardly as designated by dotted lines 38 in Fig. 4, said unfolding card dropping through the opening 32 of the housing 8 70 and finally assuming a vertical depending position as designated at 39 in the majority of the figures of the drawings.

It is obvious after 32nd Street has been 75 passed the conductor will again press the button 28 thereby energizing the magnet 25 and allowing the next sign card in order be released and descend through the opening 32 of the housing 8, thereby indicating to the passengers of the street car that the next 80 street will be 31st Street.

The operating of the button 28 by the conductor is of course repetition, and when the end of the downtown run has been reached it is quite evident that the sign card disclosing 1st Street or the like will be exposed, and assuming that 1st Street forms part of the car loop for the up town run, the next sign card operated will be that disclosing 2nd 85 Street which will be the same indication as was disclosed, but not the same particular sign card, for as afore mentioned there will be approximately the double amount of sign cards used as there are street intersections on 90 a one way run.

The members 11 and 12 bearing the plurality of sign cards are adapted to revolve in the same direction, and in this connection there will only be one sign card disclosing the looping street at each end of the round trip along which the street car is to traverse, whereas there will be two sign cards for all 100 street car intersections located between the looping streets.

Inasmuch as the drum bearing the sign 105 cards is adapted to revolve in only one direction the sign cards after being displayed as designated at 39 will be gradually elevated and wrapped in overlapping relation upon each other as they are carried on upwardly, the wrapping operation being assisted by the lip 40 which is horizontally arranged on the housing 8 to one side of the opening 32.

If for any reason a conductor overlooks 115 operating the button 28 giving a different block he can readily operate the button more times in rapid succession towards causing the desired sign card to be displayed.

A handle 41 is mounted on one end of the 120 shaft 10 for quickly turning the mechanism to a desired position whenever called for, such as when it is desired to change certain of the sign cards, so as to provide new signs with a different character of advertising matter, as this improved device as well as being adapted to street indicating will also be used as an advertising medium by displaying advertising on each sign card.

Inasmuch as this improved device is ar- 130

ranged forwardly of the car, it is obvious that the sign cards will be viewed from one side only, which will be from positions rearwardly of the device so as to be viewed by the passengers in the street car.

To prevent the rods 17 of the sign cards 15 from falling from their respective notches 13 when they assume positions below a horizontal plane with the axis of the shaft 10 a 10 curved member 42 is provided, said member being held in position by brackets such as 43 which are extended from one of the side walls 7 of the housing 8.

What I claim is:—

15 1. A sign card displaying device comprising a horizontally arranged shaft bearing a pair of rigidly secured spaced apart members, said members being for the support of a series of sign cards which are arranged so 20 as to overlap one another, means co-operable with said shaft for intermittently revolving it and said members in one direction, each of said cards being borne by said members in a manner whereby each in turn can be vertically 25 suspended therefrom, and a horizontally arranged member to be engaged by the intermediate portion of each card after each card has been suspended for assisting the overlapping operation of said cards, and a horizontally 30 arranged member to be engaged by each card after being suspended for assisting the overlapping operation of said cards.

2. A sign card displaying device comprising 35 a horizontally arranged shaft bearing a pair of rigidly secured spaced apart members, said members being for the support of a series of sign cards which are arranged so 40 as to overlap one another, each of said cards being borne by said members in a manner whereby each in turn can be vertically suspended therefrom, a ratchet wheel rigidly secured to said shaft, an armature arm 45 loosely mounted on said shaft, a pawl borne by said arm for engagement with the teeth of said ratchet wheel, an electric magnet co-operable with said arm, a normally open electric circuit co-operable with said arm and said armature which when closed is 50 adapted to cause said arm to move and the pawl borne thereby to actuate said ratchet wheel, and a horizontally arranged member 55 to be engaged by the intermediate portion of each card after each card has been suspended for assisting the overlapping operation of said cards, and a horizontally arranged member to be engaged by each card after being suspended for assisting the overlapping operation of said cards.

60 3. A sign card displaying device comprising

ing an intermittently revolvable member bearing a series of demountable flexible cards which are adapted to overlap one another, means provided whereby each card is adapted to be vertically suspended in successive 65 order from said member when each card has reached a lowered position, means provided for intermittently revolving said member, and a horizontally arranged member to be engaged by the intermediate portion of each 70 card after said cards have been suspended for assisting the overlapping operation of said cards, and a horizontally arranged member to be engaged by each card after being suspended for assisting the overlapping operation of said cards.

4. A sign card displaying device comprising a housing, a revolvable member bearing a series of flexible cards which are adapted to overlap one another located in said housing, said housing being open at its lower end, means for intermittently moving said member so that each card borne thereby can be intermittently suspended through the open end of said housing, and a horizontally extending lip formed on said housing adjacent the open end thereto to be engaged by each card after being suspendingly displayed for assisting the overlapping operation of said cards.

5. In a sign card displaying device, a horizontally arranged shaft bearing a pair of rigidly secured spaced apart members, said members being for the support of a series of sign cards, a rod from which each card is hung, one of said members being provided with a series of notches on its periphery each of which is for the reception of an end of a respective rod, said other member being provided with means for the 95 securing of the opposite ends of said rods, and a member co-operable with said notches for preventing said rods from becoming disengaged from their respective notches.

6. In a sign card displaying device, a horizontally arranged shaft bearing a pair of rigidly secured spaced apart members, said members, being for the support of a series of sign cards, a rod from which each card is hung, one of said members being provided with a series of notches on its periphery each of which is for the reception of an end of a respective rod, said other member having a series of apertures formed therein for the reception of the opposite ends of respective rods, and a curved member co-operable with said notches for preventing said rods from becoming disengaged from their respective notches.

GEORGE T. MOORE.
